UNITED STATES PATENT OFFICE

WALTER A. HEINRICH, OF ST. LOUIS, MISSOURI

EXPULSION CUT-OUT

Application filed October 22, 1928. Serial No. 314,158.

This invention relates to fuse switches and methods of making same, and particularly to the type of fuse switches known as expulsion cut-outs.

5 The rupture of fuses in electric circuits, due to the passage of excessive current, is, in most cases, accompanied by an arc which bridges the broken ends of the fuse conductor. This arc, which is due in great measure 10 to the presence of current conducting gases, is apt to reach dangerous proportions in circuits transmitting large amounts of power, and means must be provided to interrupt the arc immediately after it has been formed. 15 In the expulsion type fuse, this is accomplished by causing the rapidly expanding gases and vapors, created by the volatilized fuse wire to be expelled from the ruptured fuse conductor with sufficient force to snap 20 and extinguish the arc.

The expulsion type fuse cutout herein described, consists, in the main, of two separable parts. They are, briefly, the porcelain housing to which is secured the terminal connectors, and the fuse cartridge, which in construction is similar to a gun barrel and is adapted removably to engage the terminal connectors within the porcelain housing. When it becomes necessary to replace a broken fuse, 25 the cartridge is pulled entirely clear of the housing, the destroyed fuse removed, a new one substituted, and the cartridge replaced. Under severe short-circuit, the fuse explodes 30 with great violence, and means must be provided to prevent the cartridge being blown, due to recoil action, entirely clear of the housing. Such means are found in certain 35 of the prevailing types of fuse cutouts, to consist of locking devices which require the cartridge to be rotated with respect to the housing, or to be given some other preliminary motion before it can be removed. Operations of this nature are usually difficult to execute because of the fact that the cartridge, 40 in most cases, is handled by means of a "fuse stick" so as to permit the lineman to remain clear of live wires. The difficulty of cartridge removal is further increased by the adherence or sticking of the contacting members, caused by weathering. The provision

of improved locking and cartridge removing means forms a partial objective of the present invention.

Vitrified porcelain, because of its strength and good insulating properties, is widely used for fuse housings. A disadvantage of the use of this material, has heretofore been encountered in the difficulty of effecting a satisfactory fastening of the terminal connectors, contact clips, etc., to the porcelain, 55 due to the fact that after the porcelain has been fired, it is almost impossible to drill or thread it. The old method employed for fastening these members to the housing was to use lead or cement, but these materials 60 have proven quite unsatisfactory. When lead is used to bond a live element to the porcelain housing, conditions for condenser action are usually set up, causing sparking 65 and leakage around the porcelain which result in radio interference. The disadvantage 70 in the use of cement for the aforementioned purpose, lies in the time required for setting, and the extreme care which must be exercised in the cementing process. Where secure- 75 ment is made with lead or cement as the bond, it is usually necessary to increase the exterior diameter of the housing, as the thickness of the porcelain must be maintained throughout. The present method, to be de- 80 scribed, is directed to the elimination of the disadvantages mentioned in joining metal parts with porcelain or similar ceramic bodies.

Further difficulties arise from the fact that 85 there must be no live parts of switch or fuse, nor any screws, nuts, bolts or other live parts, exposed on the outside of the housing to become grounded or to come into accidental contact with a person working on the line.

A further object of this invention, therefore, is to provide a simple and inexpensive means and method for securing terminal connectors and the like to porcelain housings, 90 obviating the undesirable conditions previously mentioned.

A still further object is to provide improved means whereby the cartridge, when inserted into the housing, is automatically locked, no movement other than that of re- 100

placing the cartridge being required to accomplish this purpose.

Further objects are directed toward ease of operation.

Other objects and advantages will appear from the following detailed description and the accompanying illustration of a preferred embodiment of my invention, in which:

Fig. 1 is a longitudinal sectional elevation, 10 showing the parts assembled in operational relation; Fig. 2 is a plan looking into the cutout from the bottom, with the cartridge removed for clearness; and Figs. 3, 4, 5 and 6 constitute parts of an exploded elevational 15 view, partly in section, showing details of construction of a number of the major elements.

Referring by numerals to the drawing, the porcelain housing is of tubular construction, 20 its outer surface being preferably corrugated for reasons well known in the art. Grooves 5 and 6 internally disposed in the walls of the porcelain housing and at an appreciable distance from the ends, provide means for securing the upper and lower terminal connectors 7 and 8 to the housing. The housing is shown as being of lesser internal diameter between the grooves, forming shoulders 9 and 10. Obviously, the grooves 5 and 6 are 25 not required to be annular as shown, but may consist of notches or indentations internally disposed in the walls of the housing, and which will serve the same purpose as that of the annular grooves, although I prefer to use 30 the construction shown.

The lower terminal connector 8, of such a shape and size as to cause a snug fit within the housing, is provided with a central aperture 11, and with contact clips 12, adapted to 40 receive, in removable engagement, a lower fuse clamp and contact member, hereinafter described. Spaced around, and extending at an angle from the outer periphery of the terminal connector, is a plurality of prongs 45 or fingers, 13, for the purpose of holding the terminal connector securely to the porcelain housing. This is accomplished by inserting the terminal connector in the porcelain housing, and seating it firmly against the internal shoulder 10 formed by the constricted 50 central portion of the housing. The prongs 13 are then driven or pressed radially outwardly and into the grooves or notches in the housing walls, thus permanently locating the 55 terminal connector and preventing its being moved or pulled from the housing. A similar set of prongs or their equivalent 14, serves to position the terminal connector 7, disposed on the end of the housing opposite the recited 60 connector, 8. Suitable binding posts or lugs, 15 and 16, are formed on the terminal connectors to provide for engagement by the conductors, one of which is shown at 17, suitable entrance openings for the conductors being provided and one shown at 18.

The upper terminal connector and the means for securing it to the porcelain housing, are similar in general construction to those of the lower terminal connector, except that the upper connector is not provided with 70 contact clips; these clips being fastened to the upper fuse clamp and to the explosion chamber, hereinafter described.

The fuse cartridge consists essentially, of the explosion chamber 19, the insulating tube 70 20 and the lower fuse clamp and contact member 21. A porcelain closure or cap for the housing is indicated at 22 and serves also as an insulated handle for removing and replacing the cartridge. Rigidly secured to, 75 and dependent from the cap along its longitudinal axis, is a frame-like structure 23 provided with transverse members 24. The member 23 loosely engages, and is slidably associated with an exterior angulate portion of the explosion chamber 19, and acts upon the latter through contact clips 25, which are fastened to the explosion chamber by means of screws or rivets, as shown. The contact clips 25, which are preferably constructed in strip form of a good conducting and resilient metal, are bent inwardly to form an acute angle with the contact surface, 80 26. Fingers 27 preferably formed integrally with, and projecting outwardly from the contact surface 26, are adapted to be brought to register with the notches 28 in the upper terminal member 7, when the cartridge is in operative position, as shown in Fig. 1. It will be seen that, before the cartridge can be 85 withdrawn from the terminal members, the fingers 27 must be withdrawn from the notches 28. This withdrawal is accomplished, upon unseating the cap or closure member, by the novel construction of and relation between the elements 24 and 25. An outward pull on the porcelain cap forces the transverse element 24 of the frame structure 23 against the portion 29 of the contact clips, thereby constricting the clips and drawing 90 the fingers 27 out of the notches 28, and allowing the cartridge to be freely removed from the housing. From the form of connection between the transverse members 24 and the contact clips 25, it will be seen that an outward, or withdrawing movement of the handle or closure element 22, does not initially impart any movement, either to the contact clips, or to the cartridge as a whole. Continued outward movement of the member 95 23 results, first, in constricting the clips, but still without movement of the cartridge; still further movement of the handle or closure element 22 serves to apply a hammer-like blow or jar, due to the impact between 100 transverse portions 24 and the outer hook ends 30, of the clips. This lost-motion or delayed-motion connection between the fuse cartridge and handle for withdrawing it, aids materially in unseating a cartridge 105

which has been long in service, and where the contacts may have become corroded to even a small extent, or have, for any cause, any tendency to "stick".

5. The explosion chamber 19, to which contact clips are attached, is of tubular construction and closed at one end to form a breech. The opposite end is provided with threads, or the equivalent, for attachment with the insulating tube 20.

10 The fuse proper 31, consisting of a strip of low fusing temperature metal or alloy, is fastened to the explosion chamber 19 by means of set screw 32. Passing internally through the insulating tube, the fuse is doubled back on the outside of the tube, and then secured to the lower contact member 21 by means of set screw 33.

15 It is to be observed from the foregoing description that the invention provides an expedient and economical method for securing terminal connectors, contacts, and other similar parts, generally, to porcelain housings, and also locking means whereby a fuse carrying member is prevented from being removed from the housing by recoil action which results from the violent blowing of a fuse, but which means permits the fuse carrying member, under any existing condition, to be unlocked and easily removed by a single, rectilinear movement of the handle.

20 Having described a preferred embodiment of my invention, which in my present belief illustrates the best mode of applying the principles thereof, I am, at the same time, aware that the invention may be embodied in other forms, all of which are intended to be included within the scope of the following claims.

25 40. I claim as my invention:

1. In a fuse switch and the like, an enclosure, a fuse, a manipulating element therefor and locking means whereby the fuse may be released from the enclosure and disposed 35 therein for securement against expulsion, said means adapted to be operated by reciprocating movement of the manipulating element.

2. In a fuse switch and the like, an enclosure, a fuse, a manipulating element therefor, and means whereby the fuse may be placed in locked engagement with, secured against expulsion, and removed from the enclosure by movement of the manipulating element 45 entirely within a rectilinear path intersecting said enclosure.

3. In a fuse switch, an enclosure, a fuse holding element, and securing means therefor whereby said element is adapted to be withdrawn from, replaced, and locked in said enclosure against pressures internal of the enclosure, said means being operable solely by endwise movement of the element relative to the enclosure.

4. In a fuse switch and the like, an en-

closure, a fuse, a manipulating element therefor, and means whereby the fuse may be secured against expulsion pressures, within the enclosure, and released from the enclosure by rectilinear movement of the manipulating element.

5. In a fuse switch and the like, an enclosure, a fuse, a fuse manipulating element arranged for movement along its axis, and means whereby the fuse may be placed in locked engagement with, and released from the enclosure by axial movement of the manipulating element.

10 6. In a fuse switch, an enclosure, a removable fuse-holding element, adapted to be disposed within the enclosure, an insulating member for manipulation of said element and means connecting said element and member in lost-motion engagement.

7. In a fuse switch, an insulating body, a removable fuse-holder, adapted to be disposed within the body, an insulated manipulating member associated with the fuse holder and constituting a closure for the body, and means connecting the manipulating member and fuse holder, said means adapted for initiating the movement of the holder, by impact.

8. In a fuse switch, an enclosure, a removable fuse holding element, and contacts therefor adapted to be disposed within the enclosure, an insulating handle associated with said holding element and means associating said handle in lost-motion relation with said holding element and contacts.

9. In a fuse switch, an enclosure therefor, a fuse holder and contacts adapted to be disposed within the enclosure a handle for the fuse holder, and means, operatively connecting the handle, contacts and fuse holder, and adapted upon movement of the handle, to effect a movement of said contacts in advance of movement of said fuse holder.

10. In a fuse switch, an enclosure therefor, a fuse holder adapted to be removably disposed within the enclosure, a handle for manipulating said fuse holder and flexible contact members operatively connecting said fuse holder and handle.

11. In a fuse switch, an enclosure therefor, a fuse holder and contact member adapted to be removably disposed within the enclosure, a handle for said fuse holder and means associated with said handle and contact member, said means adapted to permit an initiating movement of said holder by impact, upon actuation of said handle.

12. In a fuse switch, an enclosure therefor, a fuse holder and contact members adapted to be removably disposed within the enclosure, a handle for said fuse holder, and means associated with the handle for actuating said contacts, independently of movement of said fuse holder.

13. In a fuse switch, an enclosure there-

for, a fuse cartridge removably disposed within the enclosure, a handle for actuating said cartridge, locking elements for the fuse holder and means associated with the handle for actuating said locking elements independently of the fuse holder.

14. In a fuse switch, an enclosure therefor, a fuse cartridge, and contacts carried thereby, removably disposed within the enclosure; a handle for removing and inserting said cartridge and means for permitting an unseating movement of said cartridge and contacts by impactive movement of the handle.

15. In a fuse switch, an enclosure therefor, a fuse holder removably disposed within the enclosure, a handle for said fuse holder, and combined contact members and locking elements for the fuse holder, said members serving structurally to connect said handle and said fuse holder.

16. In a fuse switch, an enclosure therefor, a fuse holder removably disposed within the enclosure, a handle for said fuse holder, and combined contact members and locking means for the fuse holder, said locking means being adapted for actuation by the handle in advance of any movement of the fuse holder.

17. In a fuse switch, an enclosure therefor, a fuse cartridge, contacts carried by said cartridge, a handle for said cartridge and means for engaging and disengaging said contact members by manipulation of the handle, and independently of movement of the cartridge.

18. In a fuse switch, an enclosure therefor, a fuse holder removably disposed within the enclosure, a manipulating element for the holder, constituting a portion of the enclosure, and a one-piece locking element and contact member associated with the fuse holder, and serving to connect the fuse holder and manipulating element.

19. In a fuse switch, a tubular enclosure therefor, a fuse cartridge removably disposed within the enclosure, contact members adapted to lock said cartridge within the enclosure, and means external to the enclosure, for effecting a movement of said contacts, independently of movement of said cartridge.

WALTER A. HEINRICH.
